November 12, 1940, Serial No. 365,230

8 Claims. (Cl. 44—9)

This application is a division of our co-pending application Serial No. 216,068, filed June 27, 1938.

This invention relates more particularly to a process of treatment applicable to lower boiling fractions of cracked distillates within the gasoline range although it is also applicable to heavier distillates produced by the fractionation of cracked products and to corresponding fractions from the primary distillation of crude petroleums or other hydrocarbonaceous materials such as coal and shale.

This process is concerned specially with the use of certain definite types of inhibitors to materially arrest the deterioration to which hydrocarbon distillates containing appreciable quantities of olefinic and other unsaturated hydrocarbons are subject. The art of using inhibitors in unstable cracked gasolines is now one of comparatively long standing and a large number of individual compounds and classes of compounds have been developed for practical use, all of which apparently possess the characteristic of being more or less readily oxidizable so that the peroxidic compounds which are primarily formed when ole-containing gasolines are in contact with air or other oxidizing gas mixtures are decomposed and the sequence of the chain reactions leading to the formation of higher boiling polymers and resinous products which cause the deterioration of the gasoline in respect to color, gum content, and antiknock value is stopped for a time depending upon the efficiency of the inhibitor, the degree of unsaturation of the oil and the extent of its exposure.

It is recognized that the inhibitor art is known to include the use of such compounds as phenols, amines, and aminophenols and crude primary products containing these compounds, and no basic claim is made therein to the broad use of any of these classes. The present invention is specially concerned with a limited group of compounds which have been found to possess good inhibiting potency combined with resistance to accidental removal by contact with water or caustic soda which occurs at many points in the storage systems of oil refineries.

In one specific embodiment the present invention comprises the treatment of unstable gasolines particularly cracked gasolines to materially arrest the deterioration thereof by adding to said gasolines relatively small percentages of disubstituted aminophenols, in which one of the amino hydrogen atoms has been replaced by an alkyl group and the other being a hydroxy alkyl group.

Compounds of the above type, in addition to

5 having high inhibiting efficiency, have been found to have considerable resistance to removal by accidental water or aqueous alkali contacts which gasolines containing them encounter under normal conditions of service in oil refineries. Typical data showing the results obtained in practice with these compounds will be given in a later section.

10 The following example is given to illustrate the general methods of preparing compounds of the present character:

N-n-butyl-N-b-hydroxy ethyl p-aminophenol

15 The tabulation given below shows the mixture of compounds which were reacted to form the desired compound:

	Parts by weight
b-Hydroxy-ethyl p-aminophenol	30.6
n-Butyl bromide	27.4
20 Sodium bicarbonate	16.8
Ethyl alcohol	200.0

25 The above mixture of compounds was refluxed for about 12 hours and the contents of the vessel were then poured into an excess of water after which the water-oil mixture was extracted with ether. The combined ether extracts were heated to distill off the ether and then subjected to further distillation at a pressure of 4 mm. absolute. A yield of 28.1 parts by weight of the desired compound boiling at 183–186° C. under the reduced pressure was obtained which amounted to 81% of the theoretical yield. A redistillation of this material showed a boiling range of 182–183° C. at the same reduced pressure. The principal reaction taking place is given by the following structural equation:

40 The present class of compounds is sufficiently potent so that only minor quantities are necessary to insure the proper inhibition of the majority of cracked gasolines. The usual amounts are 45 of the order of 0.01–0.05%, though in unusual instances amounts as high as 0.1% may be used.

50 The following table is introduced to show the character of the results obtainable in practice by the use of the present type of inhibitors although not with the intent of unduly limiting the inven-

tion's proper scope. In all cases 0.01% of the inhibitor by weight of the gasoline was used.

4. A method for stabilizing gasoline against deterioration thereof on storage which comprises

Effective inhibitor ratio	Mg./100 cc. copper dish gum			Oxygen bomb stab. ind. period, min.			Percent removed by—	
	Orig.	Water washed	Caustic washed	Orig.	Water washed	Caustic washed	Water wash	Caustic wash
Original gasoline	37	218	106	85	85	75		
N - <i>b</i> -hydroxy - ethyl - N - butyl p-aminophenol	1.38	3	7	295	170	110	60	84
N - <i>b</i> -hydroxy - ethyl - N - octyl p-aminophenol	1.38	4	5	350	235	100	43	91

The above data shows that particularly with the higher molecular weight mixed substituted compounds there is a very low percentage removal by water washing although they are considerably affected by the action of caustic soda. The "effective inhibitor ratio" used in the table indicates the relative value of the compounds based on the induction periods and referred to a standard inhibitor.

We claim as our invention:

1. A method for stabilizing gasoline against deterioration thereof on storage which comprises adding to the gasoline a relatively small amount of an N-substituted aminophenol in which one of the amino hydrogen atoms has been replaced by an alkyl group and the other by a hydroxy alkyl group.

2. A method for stabilizing gasoline against deterioration thereof on storage which comprises adding to the gasoline a relatively small amount of an aminophenol in which one of the amino hydrogen atoms has been replaced by an ethyl group and the other by a hydroxy alkyl group.

3. A method for stabilizing gasoline against deterioration thereof on storage which comprises adding to the gasoline a relatively small amount of N-n-butyl N-beta hydroxy ethyl p-aminophenol.

15 adding to the gasoline a relatively small amount of N-n-octyl-N-beta-hydroxy ethyl p-aminophenol.

5 Motor fuel comprising gasoline normally tending to deteriorate on storage and containing a relatively small amount of a N-substituted aminophenol in which one of the amino hydrogen atoms has been replaced by an alkyl group and the other by a hydroxy alkyl group.

6. Motor fuel comprising gasoline normally tending to deteriorate on storage and containing a relatively small amount of an aminophenol in which one of the amino hydrogen atoms has been replaced by an ethyl group and the other by a hydroxy alkyl group.

7. Motor fuel comprising gasoline normally tending to deteriorate on storage and containing a relatively small amount of N-n-butyl-N-beta-hydroxy ethyl p-aminophenol.

8. Motor fuel comprising gasoline normally tending to deteriorate on storage and containing a relatively small amount of N-n-octyl-N-beta-hydroxy ethyl p-aminophenol.

GUSTAV EGLOFF.
CHARLES G. DRYER.
